STEPHEN SZEKFU, OF ELLENSBURG, WASHINGTON, ASSIGNOR OF ONE-HALF TO
VICTOR E. MUNZ, OF ELLENSBURG, WASHINGTON.

HEEL FOR FOOT-GEAR.

1,099,727.

Specification of Letters Patent.

Patented June 9, 1914.

Application filed February 3, 1914. Serial No. 816,274.

To all whom it may concern:

Be it known that I, STEPHEN SZEKFU, a subject of the King of Hungary, residing at Ellensburg, in the county of Kittitas and State of Washington, have invented certain new and useful Improvements in Heels for Foot-Gear, of which the following is a specification, reference being had therein to the accompanying drawing.

10 This invention relates to heels for footgear, and has for its object to provide, in a manner as hereinafter set forth, a heel for boots, shoes and slippers to overcome the wearing off of the heel at the sides or 15 at the rear, or in other words to prevent what may be termed run-over heels when wearing a shoe provided with a heel in accordance with this invention.

A further object of the invention is to 20 provide a heel, whether high or low, for footgear, in a manner as hereinafter set forth to provide a square foundation causing the wearer to step straight due to the fact that the heel sets firmly and squarely 25 so that the wearer cannot turn the ball of the foot thereby overcoming what may be termed run-over heels.

A further object of the invention is to 30 provide a heel, whether high or low, for men's, ladies' and children's footgear, in a manner as hereinafter set forth, to prevent what is termed run-over heels and to further 35 provide a heel for the purpose set forth which can be constructed of leather, paper, wood, metal and rubber.

Further objects of the invention are to 40 provide a heel for footgear, which is simple in its construction and arrangement, affording a square foundation to the wearer of the shoe, strong, durable, thoroughly efficient in its use and inexpensive to manufacture.

With the foregoing and other objects in view, the invention consists of the novel construction, combination and arrangement 45 of parts as hereinafter more specifically described and illustrated in the accompanying drawings, wherein is shown an embodiment of the invention, but it is to be understood that changes, variations and modifications 50 can be resorted to which come within the scope of the claims hereunto appended.

In the drawings wherein like reference characters denote corresponding parts throughout the several views:—Figure 1 is

a perspective view, Fig. 2 an end elevation 55 and Fig. 3 a bottom plan of one form of a heel for footgear in accordance with this invention, Fig. 4 is an end elevation and Fig. 5 an inverted plan of another form of heel for footgear in accordance with this 60 invention, Fig. 6 is a perspective view, Fig. 7 an inverted plan, and Fig. 8 is a rear elevation of another form of heel for footgear in accordance with this invention.

Referring to Figs. 1 to 3 of the drawings, 65 9 denotes the body portion of a shoe provided with a heel referred to generally by the reference character 10. The lower lift 11 of the heel has the rear edge 12 squared and extends in a straight line from end to 70 end and at the points of mergence between said edge 12 and the rear ends of the side edges 13 of the lift, pointed corners 14 are provided. The major portion of the rear of the heel is flat as at 15 and extends downwardly and forwardly at an inclination and the major portion of each side of the heel is flat as at 16 and extends downwardly and inwardly at an inclination. Above the pointed corners 14, the rear of the heel is rounded 75 as at 17. By constructing the lift 11 in the manner as stated, a square foundation is set up and which will cause the wearer of the shoe to step straight and which will also prevent the wearer from turning the ball of 80 the foot.

Referring to Figs. 4 and 5 of the drawings, the heel is indicated by the reference character 18 and the lower lift thereof by the reference character 19. The rear edge 90 20 of the lift 19 is straight from end to end. The sides 21 of the heel 18 are rounded and the rear heel is flat as at 22 and extends downwardly and forwardly at an inclination. The rear edge 20 of the lift 19 provides a square foundation for the wearer of 95 the shoe and causes the wearer to step straight.

Referring to Figs. 6, 7 and 8 of the drawings, 22^a indicates the body portion of the 100 slipper having a heel 23^a. The lower lift of the heel 23^a is indicated at 23 and the rear edge of said lower lift 23 is straight from end to end as at 24. The side edges 25 of the lift 23 extend forwardly and inwardly at 105 an inclination, that is to say the inclination of said side edges being toward each other whereby the forward portion of the lift 23

will be of less width than the rear portion. The points of emergence between the edge 24 and the edges 25 provide sharp corners 26. The rear portion 27 of the heel 23^a is flat and extends downwardly and forwardly at an inclination and the side portions 28 are flat and each extend downwardly and inwardly at an inclination. The rear portion of the heel 23^a above the corners 26 is rounded as at 29. The setting up of the lift 23 in the manner as stated provides a square foundation and prevents the wearer of the shoe from turning on the ball of the foot and furthermore compels the wearer to step straight.

15 In Figs. 1 and 4 of the drawings, a low heel construction is set up while in Fig. 6 a high heel construction is shown.

What I claim is:—

1. A heel for footgear comprising a body portion including a lower lift, the rear edge 20 of said lift being straight, and the rear of the body portion being flattened and extending downwardly and forwardly at an inclination.

2. A heel for footgear comprising a body 25 portion having the rear edge of the tread thereof straight.

In testimony whereof I affix my signature in the presence of two witnesses.

STEPHEN SZEKFU.
